MAGNETIC RELAY WITH SPECIAL ARMATURE MOUNTING MEANS

Bertil S. Bengtsson, Hartford, Conn., assignor to
 The Hart Manufacturing Company, Hartford,
 Conn., a corporation of Connecticut

Application June 21, 1951, Serial No. 232,840

3 Claims. (Cl. 200—93)

1

The present invention relates generally to electrical relays, and more particularly to a novel and improved construction of a relay of the so-called "polarized" type which provides many new and unexpected advantages in operation and use.

It is a principal object of the present invention to provide an extremely fast acting relay and a relay which is exceedingly compact in construction. To this end it is an object of the invention to provide a unique construction of a relay employing the polarized relay principle of operation which is highly efficient in arrangement and operation of its parts, which reduces the number of air gaps to a minimum, which is fast and positive in action, which is inherently balanced, which may be readily adjusted and is sufficiently rugged to withstand sudden shock, which is simple and economical to fabricate, assemble and adjust, and which is of minimum size.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a side view of an assembled relay with the cover housing in place, which relay comprises an exemplary embodiment of the present invention;

Fig. 2 is an enlarged fragmentary side view of the relay with the cover housing removed;

Fig. 3 is a view similar to Fig. 2 with the relay turned 90 degrees;

Fig. 4 is a top view of the relay with the cover housing removed;

Fig. 5 is a cross sectional view taken along the line 5—5 of Fig. 4;

Fig. 6 is a cross sectional view taken along the line 6—6 of Fig. 4;

Fig. 7 is a cross sectional view taken along the line 7—7 of Fig. 2;

Fig. 8 is a cross sectional view taken along the line 8—8 of Fig. 2;

Fig. 9 is a fragmentary side view of the relay with cover housing and adjusting screw bracket removed; and

Fig. 10 is a diagrammatic view showing the magnetic flux paths present during the operation of the relay.

Referring to the drawings, the relay shown is mounted on a base assembly 10 which includes a

2

conventional base plate 11 having suitable connecting terminals 12 which, however, are electrically insulated from the base plate. Centrally of the base plate 11 is a tube 13 which is utilized for evacuating the relay of air and filling it with an inert gas. The tube 13 also has a positioning function as well as serving to hold the base assembly together as described hereinafter. Situated on the upper side of the base plate 11 is an insulating disc 14 on which, in turn, is positioned a mounting bracket 15. The mounting bracket, as best shown in Figs. 3 and 5, is provided with upwardly extending posts 16 at opposite sides thereof, the posts 16 being generally rectangular in cross section and being utilized for anchoring certain parts of the relay as will be described later. The central portion of the bracket 15 is recessed at 17 to receive an insulating washer 18. The upper end of the evacuation tube 13, previously referred to, is peened over the top of the insulating washer 18, thus securely fastening the base assembly together.

Secured to the side faces of posts 16, for example, by means of screws 20 are a plurality of laminated core members 21. The core laminations 21, as best shown in Fig. 9, are generally in the shape of a capital letter E, being provided with a vertical column 22 and three horizontal branches 23, 24, and 25, respectively. The core laminations 21 are preferably made in two different sizes, i. e. with lower horizontal legs 25 of different length. This permits the core laminations to be utilized facing each other without any air gaps between the base legs 25. This is accomplished by alternating core laminations of different length legs so that they may be inter-fitted with the corresponding legs of the facing core laminations. If desired, the facing core laminations could be made in one piece but this would be disadvantageous because it would complicate the winding of the coils referred to hereinafter and also would interfere with the adjustment feature.

The base legs 25 of the core laminations 21 are inserted through coil bobbins 30 on which are wound conventional coils 31. The result is that each set of facing core laminations 21 is provided with its own coil 31. The coils are connected in parallel magnetically (so that the adjacent pole faces are the same) for the reason explained more fully hereinafter, and therefore function in the same manner as though a single coil were utilized. Plural coils are utilized primarily because of space limitations and for more efficient operation. After the coils 31 and

core laminations 21 are assembled, as described, the core laminations are then fastened at the four corners to the posts 16 of the mounting bracket 15, as clearly shown in the drawings, such as by screws 26 as previously mentioned.

There is then inserted between the facing pairs of upper legs 23 and 24 of the core laminations 21 an armature assembly 40 which includes an armature 41 which is generally in the form of a square metallic plate having horizontal slots 42 milled on opposite sides thereof. Disposed centrally of the armature are projections 43 by means of which the armature may be fastened to a hinge 44. The hinge 44 is generally in the shape of a Roman numeral II as best shown in Fig. 5 and is preferably composed of thin flexible spring metal. The upper and lower bars of the spring hinge are fastened centrally thereof to the projections 43, such as by means of rivets 45.

The projecting ends of the spring hinge 44 are then clamped between two armature brackets 50 which also are generally shaped like the hinge 44, i. e. like the Roman numeral II in vertical cross section, and which are formed with the upright legs thereof projecting inwardly to engage against the projecting side legs of the spring hinge 44 as best shown in Fig. 4. The armature assembly thus clamped between the two armature brackets is then slid between the core laminations and the bases of the armature brackets 50 are then fastened to the opposite posts 16 of the mounting bracket 15 by means of screws 51. In this way it will be seen the armature 41 is disposed vertically between the upper projecting legs of the core laminations 21 and is mounted to swing about a vertical axis, although biased by the action of the spring hinge to an "at rest" position intermediate the core laminations.

There is next provided a contact finger bracket 55 preferably formed of electrically insulating material and having secured thereto and extending inwardly through a central aperture 56 a pair of contact fingers 57 which are formed of resilient metal. The contact fingers 57 may be fastened to the bracket 55 by means of rivets 54. In the embodiment shown, the bracket 55 is also provided with a metallic spacer ring 58. The flexible contact fingers 57 are inserted alongside the armature 40 and the bracket 55 is then fastened to the side of one of the armature brackets 50 by means of screws 59.

On the opposite side of the relay from the contact finger bracket there is provided an adjusting screw bracket 60. The bracket 60 is basically a metallic rectangular plate vertically slotted at the bottom edge, as shown at 61. The bracket 60 is tapped horizontally from opposite sides as shown at 62 to receive adjusting screws 63. The adjusting screws are adapted to engage against the extremities of the contact fingers 57 and thus adjustably position them relative to the armature 41. The bracket 60 is also tapped vertically as shown at 64 to receive locking screws 65 which are utilized to fix the position of the adjusting screws 63 after the contact fingers 57 have been adjusted. The bracket 60 is secured to the outer face of the adjacent armature bracket 50 by means of screws 66.

The contact fingers 57 are provided with contact points 52 which are adapted to be engaged alternately by a contact point 53 on the armature 41, depending on the direction of swing of the armature. Suitable connections (not shown) may be made, of course, between terminals 12 and the contact fingers 57, as well as between

one of the terminals 12 and the armature brackets 50. In the specific embodiment shown, for simplicity of presentation, the relay shown in the drawings is of the single-pole, double-throw type.

It will be noted, however, that even in a single-pole relay the armature 41 is preferably provided with a second contact point 53a which is provided primarily to balance the weight of the contact point 53. As will be understood, the coils 31 are also connected to terminals 12 in the usual manner.

When assembling the relay, the next step is the insertion of two permanent magnets 70 and 71 which are preferably of high coercive strength material, such as magnets formed from Alnico or the like. The magnets 70 and 71 are preferably of equal magnetic strength and are inserted between the upper portions of the core laminations 21 with like poles adjacent.

The relay is now completely assembled and, after all adjustments are made to balance the relay, the various fastening screws referred to are turned down to fix the relay parts in adjusted position. The contact fingers 57 may then be adjusted by means of setscrews 63 which, in turn, are locked by means of screws 65. Following this, the relay may be enclosed by a housing cover 75 which takes over the top of the relay and forms an air-tight connection with the base assembly 10. After evacuation of the air content of the relay and replacement with inert gas through the tube 13, the latter is pinched off and the relay is ready for operation.

It thus will be seen that there is provided a relay which is simple and easy to fabricate and assemble. Yet it includes an armature which is centrally hinged for swinging movement and which is completely balanced for such movement in response to the magnetic field created by flux lines emanating through the four projections of the core laminations (opposite pairs of the upper legs thereof) which are located at substantially the four corners of the armature. Referring to the diagrammatic view in Fig. 10, it will be seen that the relay is in balance so long as the coils 31 are not energized. The effective flux path, due to the permanent magnets alone, is shown by solid arrows having the reference numeral 80. Inasmuch as the permanent magnets 70 and 71 are situated with like poles adjacent, the flux lines will oppose each other and thus balance at one side of the armature 41 (the north side of the permanent magnets) and will travel through the armature and emanate therefrom at the opposite side to the south poles of the permanent magnets in opposite directions and thus again are in balance. However, when the coils 31 are energized, there is superimposed on the flux path pattern just previously described additional flux lines, as shown by dot-and-dash arrows 81. As previously mentioned, the coils 31 are connected in parallel (magnetically) and for purposes of illustration it is assumed that the coils 31 are energized so that the north pole is at the lefthand side, as viewed in Fig. 10. The result is that flux lines are added which unbalance the system, being additive between the armature and the core laminations at the lower lefthand corner and at the upper righthand corner, but being in opposition at the lower righthand corner and upper lefthand corner. This unbalance causes the armature to swing, as shown by heavy arrows 82. If the direction of the current in the coils 31 were reversed, of course the opposite condition would occur and

the swing would take place in the opposite direction. The diagram shows the flux paths as though there were only one set of the core branches or projections 23 or 24, it being understood that the paths through both are the same.

As a result of the construction shown, it has been found that the action of the relay is exceedingly fast with the result that the relay is particularly useful with precision instruments where time delays in actuation are critical. Furthermore, the only air gaps in the magnetic system of the relay occur at the armature so that the relay operates very efficiently and requires comparatively small electrical force for operation. Furthermore, the relay is extremely compact and accomplishes the fast action and efficient operation in a minimum of space.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim:

1. A polarized relay comprising an armature, a hinge engaging the armature at points on opposite edges thereof to mount said armature for swinging movement about a central axis extending through said points, a pair of core members disposed, respectively, at opposite sides of the hinge, each of said core members having spaced apart fingers projecting toward opposite faces of the armature adjacent the opposite edges thereof, fixed contacts situated in the space between the fingers mounted adjacent one edge of the armature, a contact on the armature cooperating with said fixed contacts, a pair of permanent magnets disposed opposite to opposite sides of the armature with like poles opposite each other located between and engaging the core members, and a coil winding on the core members.

2. A polarized relay comprising a plate-like armature, a spring hinge fastened to the midpoint of opposite edges of the armature to per-

mit swinging movement of the armature about a central axis extending through said midpoints, a pair of permanent magnets disposed in parallel arrangement on opposite sides but spaced from the armature with like poles adjacent, a pair of core members each comprising a generally U-shaped base and two pairs of spaced apart fingers, means for positioning the core members against the adjacent poles of the permanent magnets with the spaced apart fingers projecting toward the opposite edges of the opposite faces of the armature, a coil winding on the base of each core member, a pair of fixed contacts on opposite sides of the armature between the core fingers, and a cooperating contact point on the armature.

3. A polarized relay comprising a generally rectangular plate-like armature, a spring hinge fastened to the midpoint of opposite edges of the armature for mounting the armature for swinging movement about a central axis extending through said midpoints, a pair of permanent magnets disposed in parallel arrangement with like poles adjacent on opposite sides but spaced from the armature, a core on each side of the hinge and in contact with the adjacent like pole faces of the magnets, each core comprising two pairs of spaced apart fingers projecting toward the opposite faces of the armature adjacent the opposite edges thereof and a flux carrying loop between said fingers, a coil winding on the loop of each core, a mounting bracket disposed on the outer side of one core member, contact fingers extending inwardly between the core fingers from said bracket, a second bracket disposed on the outer side of the other core member, and means on the second bracket for adjusting the position of the contact fingers relative to the armature.
